UNITED STATES PATENT OFFICE.

LEWIS S. CHICHESTER, OF JERSEY CITY, NEW JERSEY, ASSIGNOR, BY DIRECT AND MESNE ASSIGNMENTS, TO CHARLES G. FRANCKLYN AND WILLIAM FOSTER, JR., OF NEW YORK, N. Y.

APPARATUS FOR PULVERIZING GRAIN, ORES, &c.

SPECIFICATION forming part of Letters Patent No. 253,344, dated February 7, 1882.

Application filed April 19, 1880. (No model.)

To all whom it may concern:

Be it known that I, LEWIS SCUDDER CHICHESTER, of Jersey City, in the county of Hudson and State of New Jersey, United States of America, have invented an Improvement in Apparatus for Pulverizing Grain, Ores, Minerals, and other Frangible Substances, of which the following is a specification.

Before my invention a blast of air had been used for giving motion to particles of sand for engraving glass, stone, and other substances, and in the grinding of grain a current of air had been employed to aid the movement of the particles between two millstones, one of which revolved, and percussion had been used for the pulverization of various substances, the same resulting from the action of rapidly revolving arms or surfaces.

In Letters Patent No. 230,468, granted to me, an issuing jet of air is described as imparting a rapid movement to grain or other material to move it along between conveying-surfaces and cause it to strike the various corrugations thereof for pulverizing such material. A chamber has also been provided, from which frangible substances have been ejected against a target and shattered, the propelling force being gunpowder, compressed air, or steam.

My invention relates to a mechanism for accomplishing the same objects by two or more successive impacts in the same apparatus, whereby the required fineness is obtained without passing the material to be pulverized through the apparatus so many times.

In carrying out my improvement I prefer to introduce the grain or other frangible material through a tube, around which is a chamber for compressed air, and an annular nozzle for the jet of air to draw the material through the central pipe and throw it with great violence against a target that is placed opposite to the issuing jet, and around this target is a case, that not only incloses the scattering fragments, but it also presents a surface against which they are brought into forcible contact by the rebound from the target, superinduced by the re-enforcing action of the current of air as it passes around the edges of the target, so that at

least two points of impact are presented to the material to be pulverized. A second chamber with compressed air and an annular nozzle will usually be employed to direct the particles from the first reduction against a second target and the interior of a second case, and thus secure the reduction of the grain or other frangible material to the requisite fineness. In all instances the current of atmosphere acting around the material to be pulverized imparts the required speed to obtain the maximum effect by the impact upon the target, and the rebound of the shattered particles from the target causes them to enter the current of atmosphere where it is traveling with the greatest velocity. Thereby the maximum velocity is reimpended, and these particles are thrown off by centrifugal action against the inside of the case, as the air is compelled to pass around the edges of the target, thus insuring the most efficient action with the use of the smallest quantity of atmosphere traveling at a speed that would not be safe or practicable with solid revolving devices.

In the drawings I have represented, in Figure 1, a section of the apparatus with two targets, and in Fig. 2 a face view of one of the targets, with the case in section at the line *xx*.

The chamber *a* is to be supplied with air from any suitable pump or compressor, and it is preferable to maintain a pressure of four hundred or five hundred pounds to the square inch. The tube *b* conveys the air to the branch pipes *c c'* and chambers *d d'*; and at *e* is a hopper with a pipe, *f*, through which the grain or other frangible material is conveyed into the apparatus. The air under the high pressure issues from the annular orifice at *g*, and, passing through the tube *h*, imparts a maximum speed to the grain or other material and throws the same forcibly against the target *k* within the case *l*. This target is by preference slightly convex. The air is deflected from such target and passes around the edges thereof, and the shattered material, rebounding through the current of air, is propelled by the action of the air against the interior of the case *l* and strikes upon the same along the portion marked *i i*, and is again shattered and

rebounds and is carried on through the tube *m*, and the additional supply of air at the chamber *d'*, issuing from the orifice *g'*, gives a fresh impetus to the frangible particles to break 5 the same against the second target, *k'*, and case *l'*. The convex shape of the target prevents the particles rebounding directly against the movement of the impelling air and causes them and the air to diverge outwardly and 10 pass more freely around the edges of the target within the case, as aforesaid, which case is sufficiently close for the material to strike and be further shattered by the second impact. The bridge for the target being behind such 15 target, and having a central support to the back of such target, the air is allowed to pass freely around the edges of the target at all sides, and there is not any support extending from the target to the nozzle or pipe from 20 which the materials are discharged against such target. The support for the target being immediately behind the point of impact renders the target more rigid and effective than it would be if supported at its edges, and the 25 cross-bar for the central support is not liable to be injured and worn by the material that is pulverized, as it is at a distance from the points of impact. More than two of these targets, cases, and air-jets may be used, if desired.

30 I claim as my invention—

1. The combination, in an apparatus for pulverizing grain, ores, and other materials, of a supply-pipe, a jet-pipe from which air under a high pressure is caused to issue, a target 35 against which the material to be shattered is

hurled, and a case surrounding the target and sufficiently close to the same to confine the air, and against which case the materials are hurled by the current of air as they are deflected from the target, substantially as set forth.

2. In an apparatus for pulverizing grain and other material, the combination, with the supply-pipe, the jet-pipe, and the target, of a case around the target, against which the material is hurled as it is deflected from the target, and 40 which case is contracted, and a second pipe, and jet-pipe, connected with the case and a second target, substantially as specified, whereby the material receives two or more shattering impacts in the apparatus, substantially as specified.

3. In an apparatus for pulverizing grain and other materials, the combination, with the supply-tube and jet-tube for air under a high pressure, of a convex target, against which the material is shattered and from which the said material passes freely as it rebounds, as set forth.

4. The combination, with the ejector and target in an apparatus for pulverizing grain and other materials, of a central support at the back of the target and a cross-bar for the same, substantially as set forth.

Signed by me this 15th day of April, A. D. 1880.

LEWIS SCUDDER CHICHESTER.
